MEANS AND METHOD OF REFRIGERATION

Application filed May 18, 1931. Serial No. 538,090.

My invention relates to refrigerating means and apparatus of the so-called vacuum type. In this type of apparatus a refrigerating medium, as water, is evaporated in a vacuum, this evaporation causing heat absorption and refrigeration.

My invention is based upon formation of such a vacuum in a very simple manner. The following descriptive experiment will 10 illustrate this simple manner of creating a vacuum.

Assume a bottle completely filled with water, from which all air has been driven out. Now, assume this bottle turned upside 15 down and with the opening connected to a liquid pump.

Now, if pump is started, the water will be pulled out of the bottle and a space of vacuum will be created. As the water is withdrawn, 20 pressure is reduced and evaporation of water will take place to fill the space above the surface. The evaporation will cause heat absorption and cooling of the remaining water

In my apparatus I do this continuously 25 and also remove the vapors formed, and once a certain point is reached, condense the vapors removed and return same to the evaporator in liquid form, again to be evaporated.

Any liquid may be used in my apparatus, 30 but for simplicity of description, water will be assumed to be the medium used. Other liquids which may be mentioned as suitable are alcohols, ethers, hydro-carbons, etc., and such liquids may be especially suited where 35 a lower temperature than 32 degrees Fahrenheit is required.

In Fig. 1, I illustrate in diagrammatic form an arrangement suitable to my purpose, and in Fig. 2, I illustrate a slight modification of one part of the apparatus. In Fig. 40 3 I show a structural modification of Fig. 1. The several parts are conventional and may be constructed in many different ways.

The principal parts of my apparatus are 45 evaporating chamber 1, condensing chamber 2, circulating pump or compressor 3, and vapor entraining column 4.

Assume water as refrigerating agent, the 50 operation of the apparatus is now as follows:—

Before pump 3, driven by motor 3a is started, water fills the apparatus up to level A. All the air is removed so that space above this line A is filled with water vapor under the pressure as a resultant of the temperature. The entire apparatus is sealed so as 55 to prevent any inflow of air, and an advantageous construction will be to also enclose the motor with the sealed parts. If we assume a temperature of 70 degrees F. throughout the parts, then the vapor pressure in the vapor space will be approximately 0.3626 lbs. absolute, thus the apparatus operates under an initial vacuum of 29.18 inches of mercury.

In larger installations, chamber 2 may be 60 vented in such a manner as to prevent inflow of air or the breaking of the vacuum, but with provision to discharge vapors or liquid as desired when pressure in this chamber is 65 above pressure outside of same. Also, a separate vacuum pump may be added to maintain necessary vacuum and remove any air which may leak into the system. In the following description it is assumed that the 70 apparatus is sealed and absolutely tight and with all the air removed, but I do not limit the construction to this arrangement. The pump 3, which may be of any construction, 75 centrifugal, gear, rotary, etc., is now started. Liquid below line A in chamber 1, pipe 4 and pipe 6 will be transferred over to chamber 2. This chamber communicates through 80 pipe 5 and nozzle 8 with entraining column 4. Nozzle 8 discharges through Venturi restriction 9 and liquid passing through 5 and 8 will entrain vapors in chamber 7, pulling same along through column 4 to suction pipe 10 of pump 3.

Now, nozzle 8 is restricted so as to permit 85 building up of the pressure in condensing chamber 2 sufficient to compress vapors present there, and by cooling same by cooling coil 2a, condensing same to liquid state.

It is seen that by this action all the vapor 90 may be condensed in chamber 2, thus filling same with liquid to level B. The liquid is thus withdrawn from chamber 1 and the 95 cubical contents or volume of the different chambers and interconnected pipes are so figured that when chamber 2, pipe 5 and en- 100

training column 4 are entirely, or nearly so, filled with liquid, the level A above chamber 1 is lowered to level C. The liquid being practically incompressible, this level C will 5 be maintained, and any addition to the liquid in the combination 2, 4 and 5, will force this additional liquid through pipe 11 with seal 11a and into chamber 1, notwithstanding pipe 11 is on suction side of pump.

10 When this phase of the operation is reached three conditions will arise.

First—no further liquid can be drawn from chamber 1 over to suction of pump 3.

Second—all the liquid handled by the 15 pump will circulate through pipe 12, chamber 2, pipe 5, entraining column 4 and back to pump through pipe 10.

Third—the removal of part of the liquid 20 from chamber 1 will lower the pressure in same and will cause evaporation from the remaining liquid. If we assume that the vapor volume in 1 and connecting pipe 6, and also space 7 is enlarged by the removal of liquid to ten times its original volume, which 25 may be easily arranged for, then the pressure being practically in inverse proportion to the volume, this pressure will drop from the original, or from 0.3626 to 0.03626 lbs.—abs., provided of course no evaporation of the 30 liquid took place. However, as soon as pressure drops evaporation will take place with absorption of heat from the liquid, and from the surrounding objects, which evaporation will cause increase of pressure to correspond 35 to the desired temperature of the object to be cooled. Using water as agent, temperature may reach 32 degrees with a drop of pressure to 0.0886 lbs. abs. per sq. in.

Vapors formed in chamber 1 will pass 40 through pipe 6 to chamber 7, there to be entrained with the liquid coming through pipe 5. The entraining column may be surrounded with cooling jacket 4c where cooling water is used to assist in condensing the vapors. 45 Vapors not condensed here, will be condensed in condensing chamber 2 under the increased pressure there.

Now, any vapors pulled in at 9 and 50 condensed in 4 or 2 will add to the liquid on the high pressure side and will force a similar amount of liquid through pipe 11 to evaporating chamber 1, thus maintaining a constant supply of new liquid to be evaporated. The entraining nozzle 8 may discharge down- 55 wards as shown, pulling along vapors which will travel downwards with the liquid similar to air bubbles in liquid compressors and barometric condensers, or the nozzle may discharge upwards or horizontally as desired.

60 I have shown in evaporating chamber 1 capillary tubes or columns 1a. These tubes or columns are made of porous material as unglazed tile, and the purpose is to increase the area of evaporating surface by capillary 65 action. Liquid will be sucked upwards into

the material of these elements and thus increase the area of liquid surface.

In Fig. 2, I show a modification of evaporating chamber 1 to increase the area of liquid surface. Liquid drawn out of the 70 chamber through pipe 11 is checked by conventional ball check 13 preventing flow back to the chamber through this line. Liquid flowing back to chamber must flow through pipe 17, ball check 14 and over pans 16 inside said chamber 1. Any suitable check valve arrangement to direct the liquid can be used.

Many other arrangements of the apparatus may be arranged and I include all such in 80 my invention to perform the work of refrigeration according to my principle of operation.

It is to be noted that although two different pressure zones are present during operation, a higher pressure and a lower pressure, no expansion valve is used. Refrigerant is fed to low pressure zone from high pressure zone without the use of expansion valve. The apparatus may be built without 90 the use of any valves, float or pressure operated. The principle of feeding liquid refrigerant to an evaporator is entirely novel and not employed in any other refrigerating apparatus. 95

In Fig. 3 I show a slight structural modification. Parts 5, 6, 7 and 8 of Fig. 1 are shown in a lower position and below the liquid level A. The parts moved down are denoted 5A, 6A, 7A, 8A and 4bA, and function similar to 5, 6, 7, 8 and 4b as shown in Fig. 1. This modification is indicated that my apparatus may be constructed in many different ways to carry out the same principle 100 of operation. 105

I claim:—

1. A method of refrigeration comprising the removal of part of a liquid contained in a vessel, thus creating a space of lowered pressure in said vessel, evaporating part of the 110 liquid remaining in said vessel into said space of lowered pressure with resultant absorption of heat, passing said produced vapor to a condensing space, liquefying said vapors and returning liquid to said vessel to make up 115 for the evaporation in said vessel.

2. Creating a low pressure in an evaporating vessel in connection with a condensing vessel by transferring part of a liquid from the first to the second vessel, evaporating the 120 liquid remaining in said evaporating vessel with absorption of heat, constantly removing vapors formed by entraining said vapors in a moving column of the liquid, thus maintaining the low pressure in said evaporating vessel, condensing said vapors and constantly returning sufficient liquid to the evaporating vessel to make up for evaporation in same. 125

3. In a refrigerating apparatus of the vacuum type an evaporating chamber con- 130

taining a liquid to be evaporated, a condensing chamber with means attached to cool and condense a vapor, communication means between said evaporating chamber and said condensing chamber, pump means to transfer liquid from a lowered pressure in said evaporating chamber against a raised pressure in said condensing chamber through said communication means, means to pass liquid from 5 said condensing chamber through a vapor entraining chamber, communication means between said vapor entraining chamber and vapor space of said evaporating chamber, means to mix and entrain vapors produced 10 in said evaporating chamber in the liquid passing through said entraining chamber and means to pass said mixture of vapor and liquid to suction side of said pump means and further means to return to said 15 evaporating chamber sufficient liquid to compensate for loss due to evaporation in same, thus maintaining a constant liquid level in said evaporating chamber during operation of the apparatus.

20 25 4. A method of refrigeration, removing vapors from an expansion space by entraining same in a moving liquid column, condensing said vapors and returning refrigerating liquid to said expansion space by volumetric 30 displacement and without the employment of an expansion valve between the condensing space and the evaporating space.

35 5. A refrigerating apparatus of the vacuum type, a condensing space and an evaporating space, means to transfer vapors from said evaporating space to said condensing space by entraining said vapors in a liquid, and means to return refrigerating medium from said condensing space to said evaporating 40 space by volumetric displacement.

45 6. In a refrigerating apparatus of the vacuum type, an evaporating space and a condensing space and means to create a lowered pressure in said evaporating space by transferring liquid from said evaporating space to said condensing space, thus increasing the volume of the vapor space in said evaporating space.

50 7. A method of refrigeration, transferring liquid from an evaporating space to a condensing space thus increasing the volume of the vapor space in said evaporating space, causing evaporation of the remaining liquid, and constantly maintaining such evaporation 55 by removing the vapors produced by entraining same in a moving body of liquid.

In testimony whereof, I have hereunto set my hand at San Diego, California, this 14th day of May, 1931.

60 BO FOLKE RANDEL.
